2,418,689

PRODUCTION OF ALKYLATED AROMATIC HYDROCARBONS

Wayne L. Benedict, Chicago, and William J. Mattox, Riverside, Ill., assignors to Universal Oil Products Company, Chicago, Ill., a corporation of Delaware

Application November 10, 1943, Serial No. 509,680

11 Claims. (Cl. 260—671)

1

The invention relates particularly to the production of di-alkyl aromatic hydrocarbons by a series of interdependent and cooperative steps in which a suitable aliphatic or naphthenic hydrocarbon containing at least 7 carbon atoms to the molecule is subjected to aromatization to produce mono-alkyl and tri-alkyl aromatic hydrocarbons, the mono-alkyl aromatic hydrocarbon being subjected to alkyl transfer reaction to produce the di-alkyl aromatic hydrocarbon and benzene, and the benzene being reacted with said tri-alkyl aromatic hydrocarbon to produce additional quantities of said di-alkyl aromatic hydrocarbon.

The charging stock to the process comprises a paraffinic and/or olefinic hydrocarbon having at least 6 carbon atoms in a straight chain and/or an alkyl cyclohexane having at least 7 carbon atoms to the molecule. It may suitably comprise hydrocarbon fractions containing one or more of these aliphatic and/or naphthenic hydrocarbons having 7, 8 and/or 9 carbon atoms per molecule, which fractions may or may not contain aliphatic and/or naphthenic hydrocarbons having 6 carbon atoms to the molecule, such as normal and cyclohexane, and/or higher boiling hydrocarbons, such as those containing 10 or more carbon atoms per molecule. A particularly suitable charging stock may comprise selected fractions of straight run gasoline containing hydrocarbons having 6 to 9 carbon atoms per molecule.

In accordance with the present invention, the charging stock is subjected to aromatization under aromatizing conditions and in the presence of suitable aromatization catalysts including, for example, the oxides of chromium, molybdenum, vanadium, etc., which preferably are deposited on aluminum oxide or other appropriate supports.

In the aromatization step of the process, the aliphatic hydrocarbons are subjected to cyclization and dehydrogenation, while the naphthenic hydrocarbons are subjected to dehydrogenation, in order to produce the corresponding mono-alkyl aromatic hydrocarbon. However, tri-alkyl aromatic hydrocarbons are also produced during the aromatization step of the process, and it is an object of the present invention to convert said mono-alkyl and tri-alkyl aromatic hydrocarbons into substantial yields of di-alkyl aromatic hydrocarbons. In accordance with the invention, the mono-alkyl aromatic hydrocarbon is subjected to conversion in the presence of selected catalysts under selected conditions of operation to produce a di-alkyl aromatic hydrocarbon and benzene. For example, toluene, which is a mono-

alkyl aromatic hydrocarbon, is so treated in order to produce xylene and benzene. The benzene is then reacted with the tri-alkyl aromatic hydrocarbon in the presence of selected catalysts under selected conditions of operation to produce additional yields of the di-alkylated aromatic hydrocarbon. Thus, for example, trimethylbenzene is reacted with the benzene to produce additional yields of xylene.

5 10 Xylenes are at present in demand for various important uses. It has recently been shown that xylenes are particularly desirable for blending in gasoline and particularly in aviation gasoline. Ortho-xylene is utilized as an intermediate in 15 the preparation of phthalic acid or similar compounds.

In a broad aspect the present invention relates to a process for producing a di-alkyl aromatic hydrocarbon which comprises subjecting hydrocarbons containing at least 7 carbon atoms to the 20 molecule to conversion under conditions to produce mono-alkyl and tri-alkyl aromatic hydrocarbons, subjecting said mono-alkyl aromatic hydrocarbon to alkyl transfer in the presence of an 25 alkyl transfer catalyst under conditions to produce said di-alkyl aromatic hydrocarbon and benzene, and subjecting said benzene and tri-alkyl aromatic hydrocarbon to alkyl transfer in the presence of an alkyl transfer catalyst under 30 conditions to produce said di-alkyl aromatic hydrocarbon.

In one specific embodiment, the present invention relates to a process for the production of xylene which comprises subjecting a hydrocarbon fraction containing straight chain paraffinic hydrocarbons having from 6 to 9 carbon atoms per molecule to aromatization in the presence of an alumina-chromia catalyst under aromatizing conditions to produce toluene and trimethylbenzene, 35 subjecting said toluene to contact with a silica-alumina catalyst at a temperature of from about 500° to about 700° C. to produce xylene and benzene, subjecting said benzene to reaction with said trimethylbenzene in the presence of a silica-alumina catalyst at a temperature of from about 40 45 400 to about 700° C. to produce additional quantities of xylene.

In another aspect the present invention relates to a process for producing a di-alkyl aromatic hydrocarbon from a mono-alkyl aromatic hydrocarbon by reacting the latter in the presence of an alkyl transfer catalyst under conditions to produce the di-alkyl aromatic hydrocarbon and benzene.

55 The catalysts utilized in the alkyl transfer

2

steps of the present process may be the same or different and may comprise composites of silica and one or more refractory oxides such as alumina, zirconia, thoria, magnesia, etc., which are referred to in the present specification and claims as silica-alumina catalysts. In addition the catalyst may be further modified by incorporating therein other refractory oxides such as molybdena, vanadia, chromia, etc. The catalyst of the present invention is preferably synthetically prepared and may be formed by the separate or simultaneous precipitation of the components and preferably is followed by purification to substantially remove alkali and alkaline earth metal compounds.

Other suitable alkyl transfer catalysts may be employed such as a solid phosphoric acid catalyst which comprises a composite of phosphoric acid and kieselguhr or other suitable carrier. It is understood that these various catalysts are not necessarily equivalent in their activity or effectiveness in catalyzing the alkyl transfer reaction.

The alkyl transfer reactions are catalyzed by the silica-alumina catalysts at a temperature within the range of from about 200° to about 700° C., a pressure of from substantially atmospheric to 1000 pounds or more per square inch, and with hourly weight space velocities of from about 0.1 to about 10. The exact temperature to be employed in either one of the alkyl transfer steps of the process will depend upon the particular hydrocarbons being reacted therein but these conditions will be within the range heretofore specified. For example, in the alkyl transfer reaction of the mono-alkyl aromatic hydrocarbon, it may be stated in general that as the alkyl side chain on the aromatic hydrocarbon increases, the temperature to be employed for its conversion decreases. Thus, ethylbenzene may be satisfactorily converted at a lower temperature than toluene: the former at a temperature of from about 200° to about 600° C. and the latter at a temperature of from about 500° to about 700° C. However, the temperature, pressure and space velocity will be correlated to produce the desired results.

As used herein, the term "hourly weight space velocity" is intended to mean the weight of oil per hour per weight of catalyst in the reaction zone.

The invention will be further explained in describing the accompanying diagrammatic flow drawing which illustrates one specific embodiment of the invention but not with the intention of unduly limiting the same.

Referring to the drawing, a suitable charging stock as heretofore set forth is introduced to the process through line 1 and is directed into aromatization zone 2. Zone 2 may comprise any suitable design in which the aromatizing catalyst is disposed and in which the charging stock is satisfactorily contacted therewith under the desired operating conditions. This zone may be of the type now known in the art as fixed bed, fluidized, or slurry operation. Aromatization is usually effected at a temperature within the range of from about 450° to about 700° C., a pressure of from substantially atmospheric to 1000 pounds or more per square inch, at a weight hourly space velocity of from about 0.1 to 5 or more. These conditions are preferably correlated in order to produce high yields of aromatic hydrocarbons per pass.

It is also within the scope of the invention to effect the aromatization reaction during the reforming of gasoline boiling range fractions such

5 as straight run gasoline, which reforming may be effected either in the presence or absence of hydrogen. Likewise, it is within the scope of the invention that aromatization in zone 2 may be effected in the absence of a catalyst, but it is preferred in this embodiment of the invention that substantial yields of aromatics are produced per pass.

10 The aromatization products are directed through line 3 into separation zone 4, which may comprise one or a plurality of suitable fractionating, absorbing and/or stripping zones, whereby the products introduced thereto may be separated into the desired fractions. In the case here illustrated, light hydrocarbons boiling below benzene 15 may be withdrawn from the upper portion of zone 4 through line 5 and may be removed from the process. A benzene-containing fraction is withdrawn from zone 4 through line 6 and may be removed from the process, but preferably at least a portion thereof is directed through line 7 for further conversion within the process in the manner to be hereinafter set forth. A toluene-containing fraction is withdrawn through line 8 and, while a portion thereof may be removed from the process, at least a portion thereof is directed through line 9 for further conversion in the manner to be hereinafter set forth.

20 When desired, an ethylbenzene fraction may be separated in zone 4 and withdrawn therefrom through line 10. A xylene-containing fraction is withdrawn from zone 4 through line 11, while a cumene-containing fraction is removed from zone 4 through line 12. A fraction containing trimethylbenzene is withdrawn from zone 4 through line 13 and, while a portion thereof may be removed from the process, at least a portion is directed through line 14 for conversion in the manner to be hereinafter set forth. Material 25 boiling higher than trimethylbenzene may be withdrawn from zone 4 through line 15 and may be removed from the process.

30 It is understood that the separation illustrated in the drawing is specific to an operation in which the charging stock supplied to aromatization in zone 2 contains straight chain aliphatic hydrocarbons having 7, 8 and 9 carbon atoms to the molecule or to a charging stock containing alkyl cyclohexanes in which the alkyl groups comprise methyl, ethyl and isopropyl radicals or to mixtures of these aliphatic and naphthenic hydrocarbons. The charging stock may or may not contain normal hexane and/or cyclohexane.

35 In cases where the charging stock contains other hydrocarbon compounds, separation in zone 4 may be modified accordingly to separate the products as desired. It is also within the scope of the invention to subject either the total products from zone 2 or any desired fraction thereof to solvent extraction or other treatment in order to separate the aromatic hydrocarbons from unconverted paraffins and/or naphthenes. The unconverted paraffins and naphthenes may be recycled, by well known means not illustrated, to the aromatization zone for further treatment therein, while the aromatic hydrocarbons may be recovered in part or subjected to further treatment in accordance with the present invention.

40 When the aromatic-containing fractions withdrawn from zone 4 for further treatment within the process contain substantial quantities of olefins, it may be desirable to subject these fractions, either together or separately, to an olefin removal step prior to the alkyl transfer reactions. The presence of substantial quantities of olefins

as, for example, in excess of 10 to 20%, may result in an excessive deposition of hydrocarbonaceous contaminants on the alkyl transfer catalyst. Any suitable means, not shown, may be utilized for the removal of the olefins, such as selective hydrogenation or solvent extraction.

The toluene-containing fraction withdrawn through line 9 is directed into alkyl transfer zone 16. Zone 16 may be of any suitable design in which the catalyst is disposed and in which the toluene fraction is contacted therewith under the desired conditions. Conversion of toluene into xylene and benzene may be effected in the presence of a silica-alumina catalyst at a temperature of from about 500 to about 700° C., a pressure of from about atmospheric to about 1000 pounds or more and preferably of from about 200 to about 500 pounds per square inch, with a weight hourly space velocity of from about 0.1 to about 10. Zone 16 may be of either a fixed bed, fluidized or other suitable type of process.

The reaction products are withdrawn from zone 16 through line 17 and, in accordance with the embodiment of the invention herein illustrated, are directed through line 3 into zone 4, wherein benzene and xylene are separated and withdrawn therefrom in the manner heretofore set forth. Any unconverted toluene is likewise separated in zone 4 and may be recycled by way of lines 8 and 9 to zones 16 for further conversion therein. It is within the scope of the invention to separate the reaction products from zone 16 in a separation zone independent of zone 4. However, in the preferred embodiment of the present invention, the reaction products from all three conversion steps of the process may conveniently be separated in common zones, thus providing a unitary and closely cooperative process and avoiding the cost of additional separation equipment.

The trimethylbenzene separated in zone 4 and withdrawn therefrom through line 13 may be directed through line 14, wherein it is commingled with the benzene withdrawn from zone 4 and directed through lines 6 and 7, and the mixture is supplied to alkyl transfer zone 18 which may be similar to or different in design than zone 16. In zone 18, the trimethylbenzene is reacted with the benzene in the presence of the catalyst to produce xylene. This reaction may be effected at a temperature within the range of from about 400° to about 700° C., a pressure of substantially atmospheric to about 1000 pounds or more per square inch and with hourly weight space velocities of from about 0.1 to about 10. The reaction products are withdrawn from zone 18 through line 19 and, while they may be subjected to separation in an independent system, they are preferably directed through line 3 into zone 4 for separation in commingled state with the other products of the process.

In an operation in which it is desired to produce di-ethylbenzene, ethylbenzene may be withdrawn from zone 4 through line 10 and may be directed, by well known means not illustrated, into alkyl transfer zone 16, while the toluene, if any, is removed from the process through line 8. The ethylbenzene may be reacted in the presence of a silica-alumina catalyst at a temperature of from about 200° to about 600° C. and preferably within the range of 250° to 550° C. to produce di-ethylbenzene. Temperatures of about 400° to about 550° C. are preferred for producing ortho-di-ethylbenzene. The reaction products from zone 16 may be subjected to fractionation

in an independent system to recover the di-ethylbenzene or the reaction products may be directed through lines 17 and 8 to separation zone 4 wherefrom the di-ethylbenzene may be recovered through line 15. These products may then be subjected to further separation, by well known means, to recover the ortho and other di-ethylbenzenes.

The following examples are introduced to further illustrate one specific operation of the process, but not with the intention of unduly limiting the same.

Example I

A straight run gasoline fraction containing hydrocarbons having 6 to 9 carbon atoms per molecule may be subjected to aromatization in the presence of an alumina-chromia catalyst at a temperature of 540° C., space velocity of 0.2 and approximately atmospheric pressure. The reaction products will contain more than 60% aromatic hydrocarbons including benzene, toluene and trimethylbenzene.

The toluene may be subjected to reaction in the presence of a silica-alumina catalyst at a temperature of 600° C., atmospheric pressure and a space velocity of 1. Under these conditions, a xylene fraction amounting to about 11% by weight of the toluene charged per pass is obtained, along with approximately an equal molecular proportion of benzene.

The benzene is commingled with the trimethylbenzene fraction and the mixture is subjected to alkyl transfer in the presence of a silica-alumina catalyst at a temperature of about 550° C., atmospheric pressure and a weight hourly space velocity of 1. Under these conditions there is produced a xylene fraction amounting to about 28% by weight of the trimethylbenzene charged per pass to this step of the process.

Example II

In this example an ethylbenzene fraction was subjected to alkyl transfer in the presence of a silica-alumina catalyst at a temperature of 300° C., and a pressure of 500 pounds per square inch to produce 20% per pass of di-ethylbenzene by weight based upon the ethylbenzene charged to this step of the process.

We claim as our invention:

1. A process for producing a di-alkyl aromatic hydrocarbon which comprises reacting a mono-alkyl aromatic hydrocarbon in the presence of a catalyst comprising a composite of silica and alumina at a temperature of from about 200° to about 700° C. and an hourly weight space velocity of from about 0.1 to about 10.

2. A process for producing xylene which comprises reacting toluene in the presence of a catalyst comprising a composite of silica and alumina at a temperature of from about 500° to about 700° C. and an hourly weight space velocity of from about 0.1 to about 10.

3. A process for producing di-ethylbenzene which comprises reacting mono-ethylbenzene in the presence of a catalyst comprising a composite of silica and alumina at a temperature of from about 200° to about 600° C. and an hourly weight space velocity of from about 0.1 to about 10.

4. A process for the production of dialkyl benzenes which comprises separating from a mixture of alkylated benzenes a monoalkyl benzene fraction and a trialkyl benzene fraction, reacting said monoalkyl benzene fraction in a first reaction zone in the presence of an alkyl transfer

catalyst to produce a dialkyl benzene and benzene, separating said benzene and reacting the same with said trialkyl benzene fraction in a second reaction zone in the presence of an alkyl transfer catalyst to produce additional quantities of said dialkyl benzene, and recovering the dialkyl benzene produced in each of said zones.

5. A process for the production of xylene which comprises separating from a mixture of alkylated benzenes a toluene fraction and a trimethylbenzene fraction, reacting said toluene fraction in a first reaction zone in the presence of an alkyl transfer catalyst to produce benzene and xylene, separating said benzene and reacting the same with said trimethylbenzene fraction in a second reaction zone in the presence of an alkyl transfer catalyst to produce xylene, and recovering the xylene produced in each of said zones.

6. A process for the production of dialkyl benzenes which comprises introducing a mixture of alkylated benzenes into a separation zone; introducing into said separation zone reaction products obtained as hereinafter described; removing from said separation zone a monoalkyl benzene fraction, a dialkyl benzene fraction, a trialkyl benzene fraction, and a benzene fraction; reacting said monoalkyl benzene fraction in a first reaction zone in the presence of an alkyl transfer catalyst to produce a dialkyl benzene and benzene; introducing the reaction products from said first reaction zone comprising dialkyl benzene, benzene and unconverted monoalkyl benzene into said separation zone; reacting said trialkyl benzene fraction with said benzene fraction in a second reaction zone in the presence of an alkyl transfer catalyst to produce an additional amount of said dialkyl benzene; introducing the reaction products from said second reaction zone into said separation zone; and recovering said dialkyl benzene fraction.

7. A process for the production of xylene which comprises introducing a mixture of alkylated benzenes containing 7, 8 and 9 carbon atoms per molecule into a separation zone; introducing into said separation zone reaction products obtained as hereinafter described; removing from said separation zone a benzene fraction, a toluene fraction, a xylene fraction, and a trimethyl benzene fraction; reacting said toluene fraction in a first reaction zone in the presence of an alkyl transfer catalyst to produce xylene and benzene; introducing reaction products from said first reaction zone comprising benzene, xylene and unconverted toluene into said separation zone; reacting said benzene fraction with said trimethyl benzene fraction in a second reaction zone in the presence of an alkyl transfer catalyst to produce xylene; introducing the reaction products from said second reaction zone into said separation zone; and recovering said xylene fraction.

8. The process of claim 4 further characterized

in that the alkyl transfer catalyst employed in each of said reaction zones comprises a composite of silica and alumina.

9. The process of claim 6 further characterized in that the alkyl transfer catalyst employed in each of said reaction zones comprises a composite of silica and alumina.

10. A process for the production of xylene which comprises introducing a mixture of alkylated benzenes containing 7, 8 and 9 carbon atoms per molecule into a separation zone; introducing into said separation zone reaction products obtained as hereinafter described; removing from said separation zone a benzene fraction, a toluene fraction, a xylene fraction and a trimethylbenzene fraction; reacting said toluene fraction in a first reaction zone at a temperature of from about 500° C. to about 700° C. and an hourly weight space velocity of from about 0.1 to about 10 in the presence of an alkyl transfer catalyst comprising a composite of silica and alumina to produce xylene and benzene; introducing reaction products from said first reaction zone comprising benzene, xylene and unconverted toluene into said separation zone; reacting said benzene fraction with said trimethylbenzene fraction in a second reaction zone at a temperature of from about 400° C. to about 700° C. and an hourly weight space velocity of from about 0.1 to about 10 in the presence of an alkyl transfer catalyst comprising a composite of silica and alumina to produce xylene; introducing the reaction products from said second reaction zone into said separation zone; and recovering said xylene fraction.

11. The process of claim 10 further characterized in that cumene is recovered from said separation zone as a product of the process.
